CALCULATING MACHINE

Kenneth Grange, London, Hampstead, England, assignor
to Maruzen Mishin Kabushiki Kaisha (Maruzen Sew-
ing Machine Co., Ltd.), Sata Moriguchi, Osaka Prefec-
ture, Japan

Filed Mar. 28, 1969, Ser. No. 16,505

Term of patent 14 years

Int. Cl. D18—01

U.S. Cl. D64—11

FIG.7

FIG.8

FIG.1

FIG.2

FIG.3

FIG4

FIG5

FIG6

FIG. 1 is a perspective view of the calculating machine showing the new design;

FIG. 2 is a top plan view thereof;

FIG. 3 is a bottom plan view thereof;

FIG. 4 is a front elevation view thereof;

FIG. 5 is a side elevation view of the right side thereof;

FIG. 6 is an elevation view of the left side thereof;

FIG. 7 is a rear elevation view thereof; and

FIG. 8 is a longitudinal sectional view of the casing taken along line 8—8 of FIG. 4.

I claim:

The ornamental design for a calculating machine, as shown.
